DESIGN FOR AN ILLUMINATED ARTIFICIAL CHRISTMAS TREE

Odilon Charette, Fitchburg, Mass.

Application July 29, 1937, Serial No. 70,722

Term of patent 7 years

To all whom it may concern:

Be it known that I, Odilon Charette, a citizen of the United States, residing at Fitchburg, in the county of Worcester and State of Massachusetts, have invented a new, original, and ornamental Design for an Illuminated Artificial Christmas Tree of which the following is a specification, reference being had to the accompanying drawing, forming part thereof, in which

Figure 1, is a front elevational view of an illuminated artificial Christmas tree, showing my new design;

Figure 2, is a side view in elevation; and
Figure 3, is a top plan view.

I claim:

The ornamental design for an illuminated artificial Christmas tree, as shown.

ODILON CHARETTE.
